US0D1098148S

(12) **United States Design Patent** (10) Patent No.: **US D1,098,148 S**
(45) Date of Patent: ** Oct. 14, 2025

(54) **DISPLAY SCREEN OR PORTION THEREOF WITH GRAPHICAL USER INTERFACE**

(71) Applicant: **Apple Inc.**, Cupertino, CA (US)

(72) Inventors: **Jeewon Choi**, San Francisco, CA (US); **Neil Patrick Cormican**, Menlo Park, CA (US); **Christopher John Sanders**, San Jose, CA (US); **Dila Sart**, San Francisco, CA (US)

(73) Assignee: **Apple Inc.**, Cupertino, CA (US)

(**) Term: **15 Years**

(21) Appl. No.: **29/918,450**

(22) Filed: **Nov. 28, 2023**

CLAIM

The ornamental design for a display screen or portion thereof with graphical user interface as shown and described.

DESCRIPTION

The sole FIGURE is a front view of a display screen or portion thereof with graphical user interface showing the claimed design.

The peripheral dashed broken lines illustrate a display screen or portion thereof, and form no part of the claimed design.

The broken lines within the peripheral dashed broken lines illustrate portions of the graphical user interface which form no part of the display.

1 Claim, 1 Drawing Sheet
